Attorney

UNITED STATES PATENT OFFICE.

BENJAMIN FRANKLIN WELLS, OF LOVELAND, COLORADO.

CLIMBING DEVICE.

1,307,468.

Specification of Letters Patent. Patented June 24, 1919.

Application filed July 6, 1918. Serial No. 243,626.

To all whom it may concern:

Be it known that I, BENJAMIN FRANKLIN WELLS, a citizen of the United States, residing at Loveland, in the county of Larimer and State of Colorado, have invented 5 certain new and useful Improvements in Climbing Devices, of which the following is a specification, reference being had to the accompanying drawings.

10 This invention relates to ladders or structures for like purposes, and particularly to that class of devices in which a standard is provided, and means operating on the standard whereby the person climbing the ladder 15 may be elevated by a step by step movement of a support upon which the person is carried.

15 The general object of this invention is the provision of a very simple ladder of this 20 construction having thereon a seat or body rest and a foot rest, and so constructed that when pressure is applied upon the foot rest, the foot rest engages with the ladder against downward movement and the seat may be 25 raised and that then upon pressure being applied downward upon the seat rest, the foot rest may be raised and thus the operator move upward on the ladder by a step by step motion, leaving both hands free.

30 A further object is to provide a construction of this character having few parts and these easily assembled and which may be firmly supported in an upwardly inclined position.

35 Other objects will appear in the course of the following description.

My invention is illustrated in the accompanying drawings, wherein:

Figure 1 is a perspective view of my im- 40 proved ladder;

Fig. 2 is a fragmentary sectional view of a portion of the standard, the saddle and the foot piece;

Fig. 3 is a top plan view of the foot piece; 45 and

Fig. 4 is a top plan view of the saddle or seat rest.

Referring to these drawings, it will be seen that my improved ladder consists of a 50 standard 10, which at its lower end is firmly attached to a base comprising the outwardly and downwardly extending members 11 attached to the standard 10 by means of the braces 12 which are nailed, bolted, or otherwise rigidly attached to the standard. One

face of the standard is formed with a series of indentations 14, these indentations constituting ratchet teeth spaced at uniform distances apart, the lower end of each indentation providing a shoulder. 60

Operating on the standard 10 and having free sliding movement thereon is the seat rest 15 which has a passage 16 through it to embrace the standard. One end wall of the passage 16 is downwardly and outwardly inclined as at 17 and this end wall is provided with the inwardly projecting tooth 18 which is somewhat downwardly inclined. The seat 19 is mounted upon the rest 15 in any suitable manner and attached to 70 the rest 15 and to the seat is a strap 20 designed to be passed over the shoulder of an operator, as illustrated in Fig. 1.

It will be obvious now that when the operator rests his full weight upon the seat 19 75 that the rest 15 will be disposed in a horizontal plane, the wall 17 will rest against the inclined toothed face of the standard 10, and that the tooth 18 will enter one of the indentations 14 and bear upon the lower 80 wall thereof and thus the seat rest be held from any downward movement.

Coacting with the seat rest 15 is the foot rest 21. This also is formed with a centrally disposed passage 22 through which the standard 10 passes, and one end wall of this passage is at right angles to the upper and lower faces of the foot rest while the other end wall 23 is inclined upward and outward. The first named end wall 24 is 90 provided with a tooth 25 which engages the indentations 14 when the opposite end of the foot rest is forced downward by pressure on the transverse bar 26. A second transverse bar 27 is attached to the upper 95 face of the foot rest above the bar 26 and is for the purpose of permitting the operator to raise this end of the foot rest so as to cant it to a position to disengage the tooth 25 from the recesses 14 and permit 100 the operator to lift the foot rest upward to a new position.

In order to prevent any lateral movement of the standard 10 when in position, I preferably attach to the upper end of the standard the guy wires 28 and preferably these guy wires are attached to a cap 29 fitting over the upper end of the standard and formed with eyes 30 to which the guy wires are attached, this cap being also formed 110

with sockets 31 which extend downward and outward at an inclination to the standard to receive braces 32 which are used when the standard cannot be rested against a wall or 5 like object, these braces 32 together with the standard forming a tripod. I do not wish to be limited to any particular construction for this purpose, however.

While the foot rest and seat rest may be 10 made of any suitable material and in any suitable manner, I preferably construct each rest of two sections of wood connected by longitudinal metallic bars bolted to the wood sections as illustrated in Fig. 3. Neither do 15 I wish to be limited to the particular construction of the base illustrated in the drawings, as this may be varied in many ways.

In operation, the user seats himself on 20 the seat 19, thus causing the seat rest 15 to operatively engage the standard so that the person is fully supported on the seat rest. His feet rest upon the cross bar 26 of the 25 foot rest which is thus canted so that the pin 24 enters one of the notches or indentations 14 in the standard. Now when it is desired to move up the ladder, the user rises to a standing position and in thus rising the strap 20 lifts the seat rest upward to a new position. The user again seats himself 30 and draws his feet upward against the upper bar 27, thus canting the foot rest so as to release the pin 25 from its engagement with the recess 14 and then lifts upward on this bar dragging the foot rest up to a new 35 position. Downward pressure on the cross bar 26 will now lock the foot rest and the seat rest may be again raised. By this means the operator may progress step by step up the standard. The descent is made 40 by first releasing the foot rest and pushing it down and engaging it with the standard and then releasing the saddle and allowing it to descend to a new position.

I claim:—

45 1. A ladder of the character described comprising a standard having ratchet teeth, a foot rest and a seat rest embracing the standard and movable along it, the seat rest being provided with means whereby it may 50 be operatively connected to the body of the user, and both of said rests being provided with means whereby they may be detachably engaged with said ratchet teeth.

55 2. A ladder of the character described comprising a standard, a foot rest and a seat rest embracing the standard and movable therealong independently of each other and adapted when shifted in one position by the operator to be raised or lowered on the 60 standard but when shifted to another position to be held against downward movement on the standard, the foot rest and seat rest being formed with means whereby they may be operatively engaged with the feet 65 and body of the operator respectively.

3. A ladder of the character described comprising a standard having ratchet indentations on one face, a seat rest slidably mounted upon the standard and having an opening through which the standard passes, 70 the opening being longer than the depth of the standard and one wall of said opening being formed with a tooth to engage said indentations and having a seat projecting out at one end, means for detachably connecting the seat rest to the operator's body, and a foot rest having an opening therethrough for the passage of the standard, the opening being larger than the depth of the standard and having a tooth engageable 80 with said indentations when the foot rest is actuated in one direction, and means engageable by the operator's feet to cant the foot rest into or out of operative engagement with the standard. 85

4. A ladder of the character described comprising a standard having ratchet indentations upon one face, a seat rest slidable on the standard and having an opening therethrough, through which the standard passes, that wall of the opening confronting the indented face of the standard being inclined downward and outward and being provided adjacent its lower end with an inwardly extending tooth, this end of the seat 90 rest being provided with an outwardly projecting seat, the seat rest having a strap whereby it may be engaged with the body of an operator, a foot rest disposed below the seat rest and slidably mounted upon the 95 standard and having an opening through which the standard passes, that wall of this opening confronting the indented face of the standard being in a plane at right angles to the upper face of the foot rest and having a tooth at its upper end engageable in the indentations of the standard, the opposite end of the foot rest having upper and lower cross bars. 100

5. A ladder of the character described comprising a standard having ratchet indentations upon one face, a seat rest slidable on the standard and having an opening therethrough, through which the standard passes, that wall of the opening confronting the indented face of the standard being inclined downward and outward and being provided adjacent its lower end with an inwardly extending tooth, this end of the seat rest being provided with an outwardly projecting seat, 110 the seat rest having a strap whereby it may engage with the body of an operator, a foot rest disposed below the seat rest and slidably mounted upon the standard and having an opening through which the standard passes, 115 that wall of this opening confronting the indented face of the standard being in a plane at right angles to the upper face of the foot rest and having a tooth at its upper end engageable in the indentations of the 120 standard passes, that wall of this opening confronting the indented face of the standard being in a plane at right angles to the upper face of the foot rest and having a tooth at its upper end engageable in the indentations of the 125 standard. 130

standard, the opposite end of the foot rest having upper and lower cross bars, the lower end of the standard being provided with a base and the upper end having means thereon whereby it may be connected to bracing members.

5 Copies of this patent may be obtained for five cents each, by addressing the "Commissioner of Patents, Washington, D. C."

In testimony whereof I hereunto affix my signature in the presence of two witnesses.

BENJAMIN FRANKLIN WELLS.
